UNITED STATES PATENT OFFICE

HARRISON DRODDY, OF EL DORADO, ARKANSAS, ASSIGNOR OF ONE-HALF TO JACK ROACH, OF EL DORADO, ARKANSAS

DEVICE FOR REMOVING AND INSTALLING SPRINGS

Application filed October 14, 1929. Serial No. 399,542.

The present invention relates to a device for removing and installing springs particularly those of the transverse type now in common use and the prime object of the invention 5 resides in the provision of an apparatus whereby the spring may be flattened out to an extended position or held in this position during the installation or removal thereof thereby making this operation comparatively easy.

10 Another very important object of the invention resides in the provision of an apparatus of this nature which is exceedingly simple in its construction, inexpensive to manufacture, strong and durable, easy to assemble 15 and disassemble, easy to operate, thoroughly efficient and reliable in use and operation, and otherwise well adapted to the purpose for which it is designed.

With the above and numerous other objects 20 in view as will appear as the description proceeds, the invention resides in certain novel features of construction, and in the combination and arrangement of parts as will be hereinafter more fully described and claimed.

25 In the drawings:

Figure 1 is an elevation of one type of spring upon which the apparatus may be used to advantage.

Figure 2 is a top plan view of the spring 30 with the apparatus associated therewith,

Figure 3 is an end view of the connecting bar,

Figure 4 is a perspective view of one of the links,

35 Figure 5 is an elevation of the spring and apparatus showing the operating means removed,

Figure 6 is a detail elevation of the connecting bar,

40 Figure 7 is a detail elevation of one of the jacks, and

Figure 8 is a detail section taken substantially on the line 8—8 of Figure 7.

45 Referring to the drawing in detail it will be seen that the letter S denotes a somewhat semi-elliptical or upwardly bowed spring such as is commonly in use on automobiles and is provided at its ends with eyes 5.

The numeral 6 denotes a connecting bar the 50 central portion 7 of which is bowed upwardly

so that it will clear the differential housing when the apparatus is being used to remove or install a rear spring. The ends of this connecting bar terminate in squared extensions 8. A pair of jacks are denoted generally by the letters J and are herein shown as of the ratchet and lever type but the operating mechanism of these jacks is not of the essence of the invention.

55 For the purpose of clearness, however, the housing portion of each jack has been denoted by the numeral 9 while the movable portion is denoted by the numeral 10. The movable portion 10 moves in and out on the outer end of the housing while on the inner end of the housing there is formed a square socket 11.

The extensions 8 are receivable in the sockets 11 so as to prevent the turning of the jacks 60 in respect to the bar although this is not of the essence of the invention.

65 The extremities of the movable parts 10 are beveled as is indicated at 12 so as to engage the eyes 5 as clearly indicated in Figure 5. An anchor in the form of a hook 14 with an eye extension 15 passing about the fender of the bar 6 is adapted to have fulcrumed thereon the lever 16 to the intermediate portion of which are pivotally engaged as at 17 a pair of links 18. These links 18 are pivotally engaged as at 19 with the handles 20 of the jack J.

70 Obviously, therefore, when the jacks are operated by the oscillation of the handle 16, the movable parts 10 may be moved outwardly from each other or inwardly from each other for stretching the spring or allowing the spring to contract.

75 Thus when the spring is detached from the automobile it is contracted to the position shown in Figure 1 and therefore may be expanded to the position shown in Figure 5 so as to be easily attached to its perch.

80 When the spring is installed on the automobile the structure may be engaged therewith and the spring disengaged from the perch and then for operating the apparatus the spring may be allowed to slowly contract to its normal position.

85 It is thought that the construction, opera- 90

tion, utility and advantages of this invention will now be quite apparent to those skilled in this art without a more detailed description thereof.

5 The present embodiment of the invention has been disclosed in considerable detail merely for the purposes of exemplification since in actual practice it attains the features of advantage enumerated as desirable in the
10 statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

20 1. An apparatus of the class described comprising a pair of jacks, a connecting bar between the jacks, a lever rockably engaged with the connecting bar, and means operatively connecting the lever with the jacks for
25 simultaneous operation thereof, each jack comprising a stationary part engaged with the bar and a movable part having a beveled terminal, the inner ends of the stationary parts of the jack having formed thereon
30 sockets, and the bar having extensions receivable in said sockets.

2. An apparatus of the class described comprising a bar having squared end portions, a rack and segment type jack having a
35 horizontally movable element for engaging the eyes of the spring, and a stationary housing, carrying an operating lever, and a socket for receiving one squared end portion of said bar, and another similar jack having a socket
40 for receiving the other squared end portion of the bar; and a detachable jack operating structure comprising a pair of handles for engaging the operating lever of the jacks, the rods pivotally connected at its ends with
45 said handles and a pintle secured to an intermediate portion of the bar and a lever pivoted at one end on said pintle and at its intermediate portion to said rod for simultaneously projecting or retracting said horizontally
50 movable elements.

In testimony whereof I affix my signature.
HARRISON DRODDY.
